[57] **CLAIM**

The ornamental design for a tire tread, as shown and
described.

DESCRIPTION

FIG. 1 is a perspective view of a tire tread showing our new
tire tread design, it being understood that the tire tread has
a pattern repeated over the outer circumference and shoulder
of a tire, the opposite side being the same as that illustrated;
and,

FIG. 2 is an enlarged fragmentary front elevation view of the
tire tread thereof.

The broken line disclosure of a tire sidewall and inner bead
is for illustrative purposes only and forms no part of the
claimed design.
